CARD SORTING MACHINE

Thomas F. Meagher, West Newton, Mass.

Continuation of application Serial No. 583,312,
March 17, 1945. This application March 18,
1950, Serial No. 150,509

8 Claims. (Cl. 129—16.1)

1

This application is a continuation of my application for "Card Sorting Machine," Serial No. 583,312, filed March 17, 1945, now abandoned.

This invention relates to card sorting and selecting machines for use in sorting cards of the character widely known as "Keysort" cards of the type which are illustrated and described in Letters Patent of the United States No. 1,544,172.

It is the principal object of my present invention to provide a generally improved apparatus capable of receiving cards of the character referred to and of operation to expeditiously sort cards disposed therein, which device is provided with a means for rapidly separating the cards being sorted to facilitate the separation of the sorted cards.

In practicing my invention I provide a sorting tray for holding the cards which is provided with templates for receiving the sorting needles or rods. When the sorting needles or rods are in position, I have provided a medium for directing a blast of air over the edges of the cards so as to expedite separation of the cards during the sorting process.

The invention is exemplified in the following description and illustrated by way of example in the accompanying drawings, in which:

Fig. 1 is a view in side elevation with parts in central longitudinal section through one form of apparatus embodying my invention.

Fig. 2 is a plan view of the same.

Fig. 3 is an end view thereof.

Fig. 4 is a perspective view of the card sorting tray.

Fig. 5 is a view in side elevation with parts in central longitudinal section through a second form of apparatus embodying my invention.

Fig. 6 is a plan view thereof.

Fig. 7 is an end view thereof.

Referring more particularly to the accompanying drawings, 10 indicates an apparatus constructed in accordance with my present invention. This apparatus is a portable one and may be disposed on a table or other convenient support for use. The apparatus is capable of use in sequence or direct sorting of edge punched cards of the type set forth in Letters Patent of the United States No. 1,544,172.

These cards are formed with a plurality of perforations disposed adjacent the edge of the card which may be separately slotted out to the edge to indicate or represent a particular classification. In direct sorting, as pointed out in said patent, those cards relating to a particular classi-

2

fication are separated from the remainder of the stack by means of a sorting rod or rods passed through the perforations of a particular classification. The rod or needles retain those cards unslotted for this classification, while the cards slotted to represent the classification separate from the stack.

In sequence sorting, as set forth in said patent, any number of cards in a stack may be placed in numerical order, or other sequence, by passing the selector rod or needle successively through the perforations in a particular sequence, as set forth in the patent. Both direct and sequence sorting is well known and, therefore, will not be described herein with any further particularity.

I also desire to point out that edge punched cards of various types are in commercial use, and that my present apparatus is applicable to edge punched cards of various types and its use is not confined solely to the particular type set forth in the aforesaid Letters Patent.

The present machine is capable of receiving a stack of cards and direct or sequence sorting the same. The apparatus comprises a frame or base 11 which, in this instance, is illustrated as a rectangular planar member. Supported by this base is a housing 12 which encloses a motor driven blower 14 of any preferred type and design having an air inlet end 15 and a discharge connection 16. In the end of the housing adjacent the air inlet end the former is provided with a series of openings 17 through which air is drawn into the housing and into the blower, when the blower is in operation. Intersecting the path of the air drawn into the housing and blower through the openings 17 are heating elements 18 so as to insure that the air delivered to the blower will be dry and heated. The housing 12 is preferably, but not necessarily, insulated for sound, as illustrated.

In the form of the apparatus shown in Figs. 1 to 4, inclusive, there is disposed on the base 11, at a spaced distance from the end of the housing 12, a pair of fixed upright supports 19 to which is pivoted a tray holder 20 at 20a so that the latter may oscillate in a vertical plane. The pivotal connections are, as illustrated, between the sides of the tray holder and the tray supports 19. As illustrated, the tray holder 20 is disposed between the supports.

For removably fitting the tray holder, I provide a sorting tray 21 to receive a stack of cards. This tray comprises three parallel template plates 22 rigidly connected by a bottom plate 23 and an end plate 24.

The top and rear edge of the template plates are perforated or punched to correspond with the perforations or punchings in the cards to be sorted. Arranged above the rigid bottom plate 23 of the tray 21 I provide a removable bottom plate 23a which is of a length agreeing with the length of the cards to be sorted. This bottom plate is receivable through a slot 29b formed in tray holder 20 and is slidably received in guides 23b formed in the sorting tray so that it may be removed just prior to the sorting operation. Plate 23a is formed with a slot 23a' in which the lowermost support 19 (as the parts are depicted in Fig. 2) is accommodated when the plate is being inserted into the tray. The distance between the top of the templates 22 and the top of this removable bottom plate 23a is such that when cards are stacked on this removable plate 23a, their top and rear edges will precisely correspond with that of the templates so that sorting needles or rods 25 may be projected through the selected punchings or holes in the templates and cards for the purpose of sorting. That is to say, the sorting needles or rods 25 are projected through the templates and cards through the punchings corresponding to the selected classifications. Thereafter the removable bottom plate 23a may be removed so that those cards which are notched in register with the sorting rods or needles 25 may lower relative to the needles and deposit on the bottom plate 23, disengaging from the needles or rods 25.

After this operation the tray holder 20 may be moved about its pivotal point to an inclined position with its front end lowermost, as shown in the drawings, so that the cards disengaged from the needles or rods 25 will slide down the tray toward the front edge thereof so that they may be removed.

I have found that in sorting stacks of cards, the cards have a tendency to adhere together so that some of the notched cards remain suspended as if unnotched. To make certain that all of the cards that are notched in register with the sorting needles or rods 25 will disengage from the remainder of the cards and drop downwardly in the tray for removal, I provide an air nozzle 26 which is connected by a rigid conduit 27 through a flexible conduit 28 to the discharge connection 19 of the blower 15. The rigid conduit 27 is guided in a guide member 29 on the frame for longitudinal movement transversely of the tray holder 20. The nozzle 26 is downwardly directed and overlies the tray holder so that a blast of air can be directed downwardly between the cards to separate the same as the nozzle is moved transversely over the top of the stack of cards. The flexible connection 28 enables this movement of the rigid conduit 27 and the nozzle 26. As the cards separate, they will descend and slide toward the front edge of the tray at a lower elevation than the cards held suspended from the needles or rods 25 and, therefore, be readily removed from the tray.

In the operation of the form of the invention shown in the figures just referred to, the sorting tray 21 is placed in the tray holder 20 with the cards stacked therein on the removable bottom plate 23a. The sorting needles or rods 25 are then projected through the punchings or perforations indicating the selected classifications. These needles or rods 25 are, of course, projected through both the templates and the cards so that they will retain those cards in the stack which are unnotched in register with the selected classi-

fications. The removable bottom plate 23a is then removed so that the cards which are notched in register with the sorting needles or rods 25 may drop from the sorting needles or rods 25 to the bottom plate 23 of the tray holder. The remaining cards, of course, will be held suspended in the sorting tray 21 on the sorting needles or rods 25. After the removable bottom plate 23a is removed, the air nozzle 26 is moved back and forth over the upper edges of the card stack to separate the selected cards from the remainder of the stack and permit the former to drop from the needles to the bottom of the tray. When the tray is inclined, the cards descend to the front end of the tray. When the cards are all separated in this fashion, those cards deposited at the front end of the tray holder may be removed.

In the form of the device shown in Figs. 5, 6 and 7 of the drawings, a pivotal tray holder is not employed. In this form of the device a rectangular cabinet 35 is substituted for the pivotal tray holder. This cabinet is provided with fixed templates 36 at opposite sides thereof which extend slightly above the open upper end of the cabinet. At the proper distance below the top of these templates is a slide 37 guided for sliding movement in the cabinet so as to form a removable bottom plate on which the cards may be stacked. Disposed in the cabinet beneath this slide is a drawer 38 mounted for sliding movement in the cabinet and removable therefrom, preferably in a direction at right angles to that of the slide 37. It is intended that this drawer receive the cards separated from the stack being sorted. I prefer that the elevation of the slide 37 in the cabinet be such that when the cards are stacked thereon in the cabinet, that the cards will be slightly inclined, as illustrated, to aid in sorting.

In operation of the form of the device shown in Figs. 5 to 7, inclusive, the slide 37 is positioned in the cabinet and the cards are stacked thereon in such an oblique position that their punched edges will correspond with the punchings in the templates 36. Sorting rods or needles 39 are then inserted through the templates and cards through the perforations representing the selected classifications. The slide 37 is then withdrawn from the cabinet 35, as illustrated, to permit the cards which are notched in register with the sorting needles or rods 39 to deposit in the drawer 38. This withdrawing action of the slide aids in separating the cards. The air nozzle 26 is moved back and forth transversely across the upper edge of the stack of cards to insure separation of all cards so that the notched or selected cards may be separated from the stack and will deposit in the drawer 38.

From the foregoing it is obvious that I have provided a card sorting device by means of which cards may be expeditiously separated, and while I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. In an apparatus of the character described, a frame, a plurality of rigidly connected laterally spaced templates carried by the frame, said templates being vertically disposed in lateral alignment and having holes formed therethrough complementary to and aligning with holes in a

stack of cards to be disposed between the templates for sorting, a removable supporting means between the templates for supporting a stack of cards in proper register therewith, selector rods for engaging the holes of the templates and stack of cards so supported for the purposes of sorting, said removable supporting means being removable from between the templates to enable selected cards to descend relative to the remainder of the stack, an air nozzle movable laterally across the top of a stack of cards disposed between the templates for directing air under pressure therebetween, and means for delivering air under pressure to said nozzle.

2. In an apparatus of the character described, a frame, a plurality of rigidly connected laterally spaced templates carried by the frame, said templates being vertically disposed in lateral alignment and having holes formed therethrough complementary to and aligning with holes in a stack of cards to be disposed between the templates for sorting, a removable supporting means between the templates for supporting a stack of cards in proper register therewith, selector rods for engaging the holes of the templates and stack of cards so supported for the purposes of sorting, said removable supporting means being removable from between the templates to enable selected cards to descend relative to the remainder of the stack, a blower carried by the frame, a nozzle connected to the blower, guide means carried by the frame and associated with the nozzle to enable the latter to be moved transversely over a stack of cards supported between the templates and direct air from the blower between the cards to separate the same.

3. In an apparatus of the character described, a frame, a plurality of rigidly connected laterally spaced templates carried by the frame, said templates being vertically disposed in lateral alignment and having holes formed therethrough complementary to and aligning with holes in a stack of cards to be disposed therebetween for sorting, a removable bottom plate disposed between the templates for supporting a stack of cards in proper registration therewith, said bottom plate being removable to enable selected cards to descend from the stack while the remainder of the cards are maintained suspended from selector rods penetrating through the holes in the templates and stack of cards, an air nozzle overlying the templates and movable transversely therebetween and thereover to direct an air blast against the upper edge of the cards to separate the same, a blower carried by the frame, a connection between the blower and said nozzle, and guiding means for said connection for guiding the said nozzle along its said movement.

4. Apparatus of the character described comprising card selector means including spaced, vertical templates formed with holes to register with holes formed in a stack of cards disposed therebetween, a support member movable to and from a position providing bottom support for the stack of cards during insertion of sorting needles, said support member being movable to allow the selected cards to drop by gravity from the stack, and air-blast means for directing a blast of air over the top edges of the stack of cards to separate selected cards and to cause them to drop from the stack, said air-blast means comprising a nozzle and a flexible connection allowing movement of the nozzle across the stack of cards.

5. Apparatus of the character described comprising card selector means including spaced, vertical templates formed with holes to register with holes formed in a stack of cards disposed therebetween, a support member movable to and from a position providing bottom support for the stack of cards during insertion of sorting needles, said support member being movable to allow the selected cards to drop by gravity from the stack, and air-blast means for directing a blast of air over the top edges of the stack of cards to separate selected cards and to cause them to drop from the stack, said air-blast means comprising a nozzle and a flexible connection allowing movement of the nozzle across the stack of cards, said nozzle being in the form of a slit extending the width of the stack of cards.

6. In a card sorting device a tray for the cards to be sorted, means for securing selected cards against movement in said tray, means for permitting movement of unselected cards, and means for separating selected and unselected cards comprising an air nozzle equal in width to the width of the cards to be sorted, a rigid air supply tube attached to said nozzle, and a guide for said tube slidably securing said tube for guided movement whereby said nozzle may be moved in a fixed path longitudinally of said tray.

7. In a card sorting device, a tray for the cards to be sorted, means for securing selected cards against movement with respect to said tray, means for permitting movement of unselected cards with respect to said tray, means for separating selected and unselected cards comprising an air chamber, openings in said chamber for admission of air thereto, air heating means within said chamber, a blower within said chamber, an air nozzle mounted over said tray, and an air conduit from said blower to said nozzle, said nozzle being equal in width to the width of the cards to be sorted and being movably disposed over said tray to be moved longitudinally thereof.

8. In a card sorting device, a tray for the cards to be sorted, means for securing selected cards against movement with respect to said tray, means for permitting movement of unselected cards with respect to said tray, means for separating selected and unselected cards comprising an air chamber, openings in said chamber for admission of air thereto, air heating means within said chamber, a blower within said chamber, an air nozzle mounted over said tray, and an air conduit from said blower to said nozzle, said nozzle being equal in width to the width of the cards to be sorted and being movably disposed over said tray to be moved longitudinally thereof, a portion of said conduit being directly attached to the nozzle and being rigid, and guide means for guiding said rigid portion for transverse movement of the nozzle over said tray in a fixed path.

THOMAS F. MEAGHER.
